Attorney

UNITED STATES PATENT OFFICE

2,316,832

FLUID MIXING DEVICE

Elie Aghnides, New York, N. Y.

Application April 5, 1940, Serial No. 328,120
In Belgium December 4, 1934

4 Claims. (Cl. 261—76)

My invention relates to a device for intimately mixing a large volume of a gas, such as air, with a liquid such as water, and ordinarily is used for producing a jet of water containing air bubbles disseminated throughout the jet and is an improvement on my Patent 2,210,846 granted Aug. 6, 1940. Such a jet is whitish in appearance, soft and light to the touch and possesses numerous advantages not found in the ordinary water jet as discharged from a faucet.

Generally speaking, my invention consists therefore of a device comprising a chamber, the inlet end of which is adapted for connection with the discharge end of a tube, such as an ordinary household water faucet, containing water under the normal main pressure of about 3 atmospheres. The outlet end of the device is adapted to discharge a coherent jet containing air bubbles disseminated throughout the jet. At the upstream end of the chamber is an apertured diaphragm through which the stream of water is adapted to be forced into the chamber with substantial velocity. An air port opening into the chamber is provided through which air is induced by the stream of water. At least one foraminous screen is provided in the path of the stream of water after it leaves the apertured diaphragm and before it discharges at the outlet end, for finely breaking up the stream of water which is thoroughly mixed with the air.

Means are provided for thereafter uniting the aerated water to form a coherent jet having small bubbles disseminated throughout the jet. This may be in part, a multiplicity of orifices in the upstream diaphragm; or in the addition of at least a second foraminous screen between the first screen and the outlet end, with openings so close to each other that the issuing aerated water unites to form a coherent jet; or, in the addition of a tubular portion at the outlet end and adapted to contract the stream of aerated water issuing from the screen, to form a coherent jet.

Referring to the drawing

Fig. 1 is a vertical section of one form of my invention.

Figs. 2 and 3 are similar sections of modified forms.

In Fig. 1, I employ the same type of rubber tap connector 2 as in Fig. 1 of my aforesaid patent, except that I provide a constricted orifice 17, above the upstream apertured diaphragm 18, and the air inlets 19 terminate close to the surface of the downstream screen 20.

In Fig. 2, I employ a screw coupling 21 having a restricted orifice 22 for connecting my device to

a faucet and I employ two spaced apertured diaphragms 23, 24 located above the air inlets 25 and I use three spaced screens 26, 27, 28, in the downstream end of the device.

5 In Fig. 3, I employ the same general type of rubber tap connector 30 as in Fig. 1. The metal coupling 31 having a restricted orifice 32 is secured thereto. Screwed to the coupling is the lower portion 33, provided with air inlets 34, an upstream diaphragm 35 having a single orifice 36 and five spaced wire screens 37, 37a, 37b, 37c, and 37d. The number of screens used depends on the orifice area, the distance between the diaphragm and screens and the mesh of the wire screens. 10 I have found that when the water is discharged through a restricted orifice, as at 17, Fig. 1, at 22 Fig. 2, and at 32 Fig. 6 that the flow through the orifices in the upstream diaphragm is improved and a more regular and softer jet is delivered from the outlet end of the device.

15 A similar result is obtained when instead of the restricted orifice upstream of the diaphragm, a second foraminous diaphragm as 23, Fig. 2, preferably with greater aggregate cross section 23 of the foramina, is located upstream of the first diaphragm 24, at a distance of about 1 mm. Both the restricted orifice and the second diaphragm can be used together for a more uniform flow of the bubbly jet.

20 This application is a continuation in part of my applications Ser. No. 182,884 filed Dec. 31, 1937 patented August 6, 1940, Number 2,210,846 and Ser. No. 52,923 filed Dec. 4, 1935.

I claim:

25 1. A device for producing a jet of water containing air bubbles comprising a chamber the inlet end of which is adapted for connection with the discharge end of a faucet or the like and the outlet end of which is adapted to discharge 40 said jet, an apertured diaphragm at the upstream end of the chamber through which water is adapted to be forced into the chamber with substantial velocity, an air port opening into the chamber through which air is induced by the water delivered from the apertured diaphragm and means in the path of the water after it leaves the apertured diaphragm and before it discharges at the outlet end for finely breaking up the water and mixing it with air to form a coherent jet having bubbles and a foraminous member upstream the apertured diaphragm.

45 2. A device for producing a jet of water containing air bubbles comprising a chamber the inlet end of which is adapted for connection with the discharge end of a faucet or the like and the

outlet end of which is adapted to discharge said jet, an apertured diaphragm at the upstream end of the chamber through which water is adapted to be forced into the chamber with substantial velocity, an air port opening into the chamber through which air is induced by the water delivered from the apertured diaphragm and means in the path of the water after it leaves the apertured diaphragm and before it discharges at the outlet end for finely breaking up the water and mixing it with air to form a coherent jet having bubbles and a restricted orifice upstream the apertured diaphragm.

3. A device for producing a jet of water containing air bubbles comprising a chamber the inlet end of which is adapted for connection with the discharge end of a faucet or the like and the outlet end of which is adapted to discharge said jet, an apertured diaphragm at the upstream end of the chamber through which water is adapted to be forced into the chamber with substantial velocity, an air port opening into the chamber through which air is induced by the water delivered from the apertured diaphragm and

means in the path of the water after it leaves the apertured diaphragm and before it discharges at the outlet end for finely breaking up the water and mixing it with air to form a coherent jet having bubbles and a restricted orifice and foraminous member upstream the apertured diaphragm.

4. A device for producing a jet of water containing air bubbles comprising a chamber the inlet end of which is adapted for connection with the discharge end of a faucet or the like and the outlet end of which is adapted to discharge said jet, superposed apertured diaphragms at the upstream end of the chamber through which water is adapted to be forced into the chamber with substantial velocity, an air port opening into the chamber through which water delivered from the apertured diaphragms and means in the path of the stream of water after it leaves the apertured diaphragms and before it discharges at the outlet end for finely breaking up the water and mixing it with air to form a coherent jet having bubbles.

ELIE AGHNIDES.
